UNITED STATES PATENT OFFICE.

JESSE B. SKEEN AND JOHN M. GRAFTON, OF SAN FRANCISCO, CALIFORNIA.

SHIFTING DEVICE FOR TYPE-WRITING MACHINES.

No. 831,387.

Specification of Letters Patent.

Patented Sept. 18, 1906.

Application filed August 9, 1905. Serial No. 273,329.

To all whom it may concern:

Be it known that we, JESSE B. SKEEN and JOHN M. GRAFTON, citizens of the United States, and residents of San Francisco, in the county of San Francisco and State of California, have invented a new and Improved Shifting Device for Type-Writing Machines, of which the following is a full, clear, and exact description.

10 Our invention relates to a device to be applied to those type-writing machines which have a single keyboard requiring the operating of one or more shifting-levers in order to provide for printing the upper and lower case characters. Ordinarily these shifting-levers are manipulated by the left hand, which action necessarily destroys the utility of that hand to a certain extent, especially in statement work or work where there are frequent 15 changes from figures to letters or other characters.

The principal object of this invention is to overcome this difficulty and place such machines on an equal footing in this respect 20 with those having double keyboards, so that they may still retain their superior advantages in certain other respects over those machines which have a separate key for each character. In order to accomplish this result and secure other advantages which will appear below, we provide machines of this character with a device for operating the shifting-levers by a simple movement of the knee of the operator, thereby leaving the left hand free for manipulating the keys and securing these advantages at very small expense and with very little addition to the operating parts of the machine.

Reference is to be had to the accompanying 25 drawings, forming a part of this specification, in which similar characters of reference indicate corresponding parts in all the figures.

Figure 1 is a perspective view of a type-writing machine with our improvement applied thereto. Fig. 2 is a longitudinal sectional view of a portion of the same, showing the attachment on an enlarged scale. Fig. 3 is a sectional view on the line 3 3 of Fig. 2, and Fig. 4 is a sectional view on the line 4 4 30 of Fig. 2.

We have represented a type-writing machine *a*, mounted upon a table *b*, which may be of any desired character. The machine may be of any of the usual types—as, for example, the Oliver—and is provided with a

pair of shift-levers *c* and *c'*. We provide the shift-levers with a pair of hooks *d* and *d'* or with any desired means for operating upon them to manipulate them in the usual manner. These hooks are connected, by means 60 of flexible connections *e* and *e'*, with a lever *f*. These flexible connections pass through openings *b'* in the table *b*, and these openings or perforations form practically the only modification that has to be made of the table, desk, or other supporting means for the machine. After passing through these perforations the flexible connections pass over pulleys *g* and thence along a curved or segmental surface *f'* of the lever *f*. These flexible connections extend in opposite directions from the center of the lever or of this curved surface and pass through openings *f''* near the two ends of said surface. Setscrews *h* are provided for securing these connections at any desired position in these openings. The lever *f* is mounted on a pivot *k*, which is preferably at the center of the curve forming the surface *f'*, and below this pivot the lever is provided with a curved 70 lower surface *f''*, adapted to engage the knee of the operator and fit above it. This curved surface is provided with depending portions *f'''* for engaging the sides of the knee, so as to insure that a motion of the knee to the right 75 or left will swing the lever about its pivot and operate the desired one of the connections *e* and *e'* to depress the proper shifting-lever. The pivot *k* is preferably in the form of a stud passing through the lever and also passing 80 through a frame *m*. This frame is provided with a boss *m'* for receiving the stud and also for receiving the lever *f*. The frame is provided also with flanges *m''*, between which is received a bracket *o*, secured to the bottom 85 of the table and depending therefrom. This bracket is provided with a slot *o'*, and a screw *p* passes through this slot into a screw-threaded opening in the frame *m*. This screw also passes through an opening in a 90 sliding plate *q*, mounted on the back of the bracket *o*. It will be seen that by loosening the screw *p* the frame *m* and slide *q* can be raised or lowered in accordance with the height of the table, so that the curved surface 95 *f''* will come in the proper position to receive the knee of the operator, and when this is properly adjusted the screws *h* are loosened and the connections *e* and *e'* drawn to a proper position to operate the shifting-levers. 100 105 110

By the use of a device constructed upon the principle illustrated above, whether of the form shown or in any other form falling within the scope of the appended claims, we secure several advantages. Among others may be mentioned the fact that when used in connection with the class of machines mentioned above it will increase the capacity fully twenty-five per cent. in estimate and statement work. It lessens the probability of mistakes by striking the wrong keys, as the board is left entirely unobstructed by the shifting operation. It more evenly distributes the work of the type-writer operator, it bringing the knee into action and relieving the left hand of the extra duty of shifting the carriage. Consequently more work and work of a better character can be done in a given time and with less effort than has heretofore been the case. Also the "touch" system of writing, which is exceedingly difficult with machines having double shifts, where such levers must be worked by hand, can be efficiently used with the assistance of this device. The attachment is exceedingly simple and is easily applied and adjusted, the only change in the table or machine being the drilling of two small holes through the top of the type-writer stand for the passage of the cords *e* and *e'* and the application of the hooks of the shifting-levers.

Having thus described our invention, we claim as new and desire to secure by Letters Patent—

- 35 1. A device for operating the shift-levers of type-writing machines, comprising a lever having a curved lower surface for receiving the knee of the operator, and connections between the shift-levers of the machine and the adjacent sides of the upper surface of the lever, whereby movement of the lever in one direction will operate one of the shift-levers, and a movement in the opposite direction will operate the other shift-lever.
- 45 2. A device for operating the shift-levers of a type-writing machine, comprising a lever located below the machine and having a curved lower surface for receiving the knee of the operator, said lever being pivoted at a point above said curved surface, and connections between the shift-levers of the machine and the adjacent sides of the upper surface of the lever, whereby movement of the lever in one direction will operate one of the shift-levers, and a movement in the opposite direction will operate the other shift-lever.
- 55 3. A device for operating the shift-levers of a type-writing machine, comprising a pivoted lever having a lower surface adapted to receive the knee of an operator, an upper curved surface drawn from the pivot of the lever as a center, and flexible connections secured to the lever at the sides of said upper

curved surface and connected with the shift-levers.

4. In an attachment for type-writing machines, the combination of a lever having a curved surface, a pair of flexible connections secured each at one end of said curved surface, means for guiding said connections along the curved surface, and means for connecting the connections with the shift-levers of the type-writing machine, said connections passing normally over the curved surface at the center thereof when said surface is in neutral position.

5. An attachment for type-writing machines provided with a plurality of shift-keys, comprising a pivoted lever, flexible connections between the shift-levers of the machine and the opposite sides of the lever, and means for adjusting the length of said connections.

6. An attachment for type-writing machines provided with a plurality of shift-keys, comprising a pivoted lever, flexible connections between the shift-levers of the type-writing machine and the opposite sides of the lever, means for adjusting the length of said connections, and means for adjustably mounting said lever.

7. In an attachment for type-writing machines, the combination of a pivoted member, a pair of flexible connections, means for adjustably securing said connections to the lever, means for connecting said connections with the shift-levers of the type-writing machine, and means for adjustably mounting said lever, said means comprising a bracket having a slot, a frame slidable along the bracket and having means for supporting the lever and means for securing the frame to the bracket at any desired position in said slot.

8. The combination with a type-writing machine having shift-levers, of a hook connected with each shift-lever, a flexible connection attached to each hook and passing downwardly therefrom and outwardly from each other at a point below the machine, and a lever to which said connections are secured, said lever being pivoted at a point below said connections and being provided with a curved surface for receiving the lower ends of said connections, said curved surface being concentric with the pivotal point and said lever also being provided with a lower curved surface and depending projections adapted to receive the knee of an operator.

In testimony whereof we have signed our names to this specification in the presence of two subscribing witnesses.
